TEETER ROCKER

Wesley K. Walton, Santa Clara County, Calif.

Application September 15, 1952, Serial No. 21,456

Term of patent 3½ years

(Cl. D34—15)

To all whom it may concern:

Be it known that I, Wesley K. Walton, a citizen of the United States, residing in the county of Santa Clara, State of California, have invented a new, original, and ornamental Design for a Teeter Rocker, of which the following is a specification, reference being had to the accompanying drawing, forming a part thereof.

Figure 1 is a plan view of the teeter rocker, showing my new design;

Figure 2 is a side elevational view of one of the two identical sides of the teeter rocker;

Figure 3 is an end elevational view of the two identical ends; and

Figure 4 is a perspective view of the teeter rocker.

I claim:

The ornamental design for a teeter rocker, as shown and described.

WESLEY K. WALTON.
